(57) **CLAIM**

The ornamental design for a hand warmer, as shown and described.

DESCRIPTION

FIG. 1 is a front and top perspective view of a hand warmer, showing my new design;

FIG. 2 is a rear and bottom perspective view thereof;

FIG. 3 is an exploded view thereof;

FIG. 4 is a front and top perspective view of a first piece of the hand warmer;

FIG. 5 is a rear and bottom perspective view thereof;

FIG. 6 is a front elevation view thereof;

FIG. 7 is a rear elevation view thereof;

FIG. 8 is a left side elevation view thereof;

FIG. 9 is a right side elevation view thereof;

FIG. 10 is a top plan view thereof;

FIG. 11 is a bottom plan view thereof;

FIG. 12 is a front and top perspective view of a second piece of the hand warmer;

FIG. 13 is a rear and bottom perspective view thereof;

FIG. 14 is a front elevation view thereof;

FIG. 15 is a rear elevation view thereof;

FIG. 16 is a left side elevation view thereof;

FIG. 17 is a right side elevation view thereof;

FIG. 18 is a top plan view thereof; and,

FIG. 19 is a bottom plan view thereof.

The broken lines in the figures illustrate portions of the hand warmer that form no part of the claimed design.
